UNITED STATES PATENT OFFICE.

JULES H. VENON, OF NEW YORK, N. Y.

DESIGN FOR A PLATE OR SIMILAR ARTICLE.

40,744.

Specification for Design. Patented June 28, 1910.

Application filed April 5, 1910. Serial No. 553,671. Term of patent 7 years.

To all whom it may concern:

Be it known that I, JULES H. VENON, a citizen of the United States, and resident of the city, county, and State of New York, have invented a new, original, and ornamental Design for Plates or Similar Articles, of which the following is a specification, reference being had to the accompanying drawing, forming part thereof.

The figure is a plan view of a plate or similar article, showing my new design therefor.

The design comprises a plate or similar article having a decoration placed around the edge thereof, composed of flowers and leaves, substantially as shown in the drawing.

I claim:

The ornamental design for a plate, or similar article, as shown and described.

JULES H. VENON.
